UNITED STATES PATENT OFFICE.

AUGUST BROCKSCHMIDT AND CLEMENT L. STUCKEY, OF PIERCE CITY, MISSOURI.

LOCK FOR AXLE-SKEIN NUTS.

SPECIFICATION forming part of Letters Patent No. 624,619, dated May 9, 1899.

Application filed June 2, 1898. Serial No. 682,391. (No model.)

To all whom it may concern:

Be it known that we, AUGUST BROCKSCHMIDT and CLEMENT L. STUCKEY, citizens of the United States, residing at Pierce City, 5 in the county of Lawrence and State of Missouri, have invented a new and useful Lock for Axle-Skein Nuts, of which the following is a specification.

Our invention is in the nature of a lock for 10 axle-skein nuts, the object of the invention being to provide a simple, cheap, and easily-applicable device whereby the nuts which hold a wagon-wheel in place will be prevented from being lost off, especially when backing 15 the wagon, thereby obviating the trouble, annoyance, and positive danger to life and property caused by such accidents.

With this object in view the invention consists in a clip made of sheet metal having a 20 rectangular central opening in its center to fit over a square end of an axle and having upper and lower horizontal flanges to embrace the top and bottom of the nut, the upper flange being bent downward at its inner 25 edge to engage in a groove in the top of the nut and the lower flange being provided with a plate-spring secured to its inner side to engage in a like groove in the bottom of the nut.

Our invention further consists in the improved 30 construction, arrangement, and combination of parts hereinafter fully described and afterward particularly pointed out in the claims.

In order to enable others skilled in the art 35 to which our invention most nearly appertains to make and use the same, we will now proceed to describe its construction and operation, having reference to the accompanying drawings, forming part hereof, in which—

Figure 1 is a perspective view of the hub and 40 part of the spokes of a wheel mounted on an axle having the skein-nut secured in place by means of our invention. Fig. 2 is a view illustrating the axle and skein in elevation and 45 the nut and lock in section. Fig. 3 is a view of the same parts all in elevation. Fig. 4 is a detail perspective view of the nut, and Fig. 5 is a detail perspective view of the lock.

Like letters of reference indicate the same 50 parts in all the figures of the drawings.

Referring to the drawings by letters, A in-

dicates a wheel-hub, and B the spokes, the wheel being of such construction as is usually used on an axle C with skein D.

E indicates the nut to hold the skein on the 55 axle, the axle being provided with a square reduced end G.

H indicates our improved locking attachment, being a metal clip comprising a main body I, with central rectangular opening J 60 to engage over the square end G of the axle and flanges K and L to embrace the top and bottom of the nut, an inwardly-turned flange K' on the flange K to engage in the groove in the top side of the nut, and a plate-spring L', 65 secured to the inside of the flange L, to engage in a like groove in the bottom side of the nut.

When the skein is in place on the axle and the nut turned up to it, the lock may be grasped between the thumb and fingers and 70 the spring pressed upward against the under side of the nut until the vertical flange K' may be passed over the top of the nut, when the whole device may be pressed inward until the flange K' and spring L' drop into their respective grooves. To remove the lock, grasp it in the same way and press upward, squeezing the spring until the flange K' is clear of its groove, and then draw the flanges K K' off the nut, when the whole device may be removed. 75 The opening J is of the same width as the reduced square end G of the axle, but is of a length sufficiently greater to permit of the movement up and down of the lock required in affixing and removing it. It may be formed 80 by cutting or punching all the material out of the sheet or by turning part of it out, as at J', to form flanges to bear against the sides of the reduced end G of the axle.

The terms "top and bottom flanges" and 90 "top and bottom sides of the nut" are used herein only with reference to these parts in the positions illustrated in the drawings, the flanges being adapted to the grooved sides of the nut no matter in what position the nut is 95 placed.

The construction, operation, and advantages of our invention will be readily understood from the foregoing, and while we have illustrated and described the best means now 100 known to us for carrying out our invention we do not wish to be understood as restrict-

ing ourselves to the exact forms and constructions shown, but hold that any slight changes or variations therefrom, such as might suggest themselves to an ordinary mechanic after having seen our invention, will clearly be comprehended within the limit and scope of our invention.

Having thus fully described our invention, what we claim as new, and wish to secure by

10 Letters Patent of the United States, is—

15 1. A locking device for nuts of axle-skeins, comprising a metallic plate or sheet having a rectangular opening to engage the reduced square end of an axle, top and bottom flanges to engage over the top and bottom sides of the nut, a vertical inwardly-turned flange at the inner end of the top flange to engage in a groove in the top of the nut, and a plate-spring secured to the inside of the bottom flange to 20 engage in a groove in the bottom side of the nut, substantially as described.

25 2. The combination with an axle having a threaded portion and a reduced square end, of a nut threaded on the axle having grooves in its top and bottom sides, and a locking at-

30 tachment consisting of a plate having a rectangular opening fitting over the reduced square end of the axle, top and bottom flanges embracing the nut, an inward flange at the inner end of the top flange engaging in the groove in the top of the nut, and a plate-spring secured on the inside of the bottom flange and engaging in the groove in the bottom of the nut, substantially as described.

35 3. In a nut-lock, the combination with a bolt, and a nut having grooves formed in its opposite edges, of a locking-plate having a bolt-opening formed with flanges adapted to engage upon opposite sides of the bolt, and formed on opposite edges with flanges, one of 40 said flanges having an inwardly-turned edge adapted to engage the groove formed in the opposite edge of the nut, substantially as described.
